UNITED STATES PATENT OFFICE.

HENRY BRUBAKER, OF YORK, PENNSYLVANIA, ASSIGNOR OF TWO-THIRDS TO HENRY D. HERSHY, OF COLUMBIA, PENNSYLVANIA.

ROLLER.

No. 901,873.

Specification of Letters Patent.

Patented Oct. 20, 1908.

Application filed July 9, 1907. Serial No. 382,858.

To all whom it may concern:

Be it known that I, HENRY BRUBAKER, citizen of the United States, residing at York, in the county of York and State of Pennsylvania, have invented certain new and useful Improvements in Rollers, of which the following is a specification.

The present invention consists of certain new and useful improvements in rollers. 10 One of the objects of the invention is to provide a roller which may be built up from strips or sections of wood.

Another object is to provide a novel means for holding the strips in a cylindrical form. 15 A further object is to provide a novel form of attachment by means of which the roller may be connected with a source of rotary power.

Other and further objects and advantages 20 of the invention will be apparent from the following detailed description, pointed out in the claims, and illustrated in the accompanying drawings.

Referring to the accompanying drawings, 25 in which like characters of reference refer to corresponding parts,—Figure 1 is a perspective view of the roller. Fig. 2 is a longitudinal sectional view thereof. Fig. 3 is a perspective view of the supporting frame, 30 the same being shown detached from the roller. Fig. 4 is a detail view of one of the strips.

The roller forming the present invention may be used in connection with various types 35 of roller machines and is of special utility in the printing, paper making, textile and kindred arts. In such machines the rollers are used for various purposes, such as printing and embossing, pressing, burnishing and 40 conveying. And in order to provide a roller that may be used for any of the above or analogous purposes, it is necessary that the roller should be made of strong material to withstand the varying pressures and strains 45 incident to a rapidly rotating roller. And also means must be provided which will permit of the roller being readily connected with the source of power of the machines.

It has been found in the practical use of 50 rollers for machines as specified above, that it is necessary to reinforce them in order to stand the strains and pressures to which they are subjected, and in order to provide a satisfactory structure, the present invention has been designed, which structure is

described and illustrated in its preferred embodiment in the following detailed description and accompanying drawings.

Referring to the drawings, 10 designates a roller in its entirety, which is composed of 60 a plurality of longitudinal strips 11 of wood. Said strips 11 are turned in a lathe or the like, to provide a convexed outer surface and a concaved inner surface, and their longitudinal edges are inwardly inclined, to provide a wide outer surface and a narrow inner surface, the arrangement being such that when the strips are assembled with their longitudinally inclined edges 12 abutting one another, a cylinder will be formed. 70

Referring more particularly to Fig. 4 of the drawings, it will be observed that the lower corners of the inclined longitudinal sides of the strips 11, are cut-away to form one half of a longitudinal recess which, when 75 the strips are assembled in cylindrical form, form longitudinally extending recesses 14, provided with a bottom wall 15 and inwardly inclined end walls 16, 17. The supporting frame 18 comprises a plurality of spaced- 80 apart longitudinal keys 19 arranged in cylindrical form. The shape of said keys 19 are substantially the same as the longitudinal recesses 14 of the strips 11, and in length 85 they correspond with said strips. 20, designates a metal shell or tube which supports the keys 19 in the desired spaced apart position, the keys being rigidly held on said shell or tube by means of the bolts or screws 23.

By referring to Fig. 3 of the drawings it 90 will be observed that each end of the shell or tube 20 has located therein a supporting ring 21—22, each of which are provided with wedge-shaped slot or keyway 24, the outer end of which is comparatively deep and 95 from which end its depth decreases until it reaches the inner end, at which point it terminates flush with the inner surface of the said ring or collar. The function of said slot or keyway will be set forth presently. 100

In assembling the parts in their operative position, the rings are placed within each end of the tube or shell and the wedge-shaped keys are then attached to the shell or tube by means of bolts or screws, in the 105 desired spaced-apart position. The strips are then driven in between the wedge-shaped keys, the cut-away portion of each strip snugly fitting over one side and one-half of the outer surface of said keys. When all 110

the strips have been placed in position on the wedge-shaped keys, a cylindrical structure such as shown in Fig. 1 of the drawings is formed, in which the strips, by means of 5 their cut-away inner portions, form a socket, or recess for the reception of the keys, the connection therebetween being in the form of what is known as a "dovetail."

To attach the roller to a source of power, 10 the stub end of a power shaft is inserted into the collars in the ends of the supporting shell or tube and may be securely and relatively immovably held therein, by means of a key or the like driven into the slot or keyway 24. 15 From the foregoing description it will be seen that a roller has been produced that is of sections, or strips of wood, and that by means of the inner supporting tube or shell and the fastening keys carried thereby, such 20 strips are firmly and rigidly held in such a manner as to serve all the functions of a continuous cylindrical roller, and one in which the injurious effects of the centrifugal force incident to the operation of the rollers 25 has been obviated. And it will be further understood that by means of the inner shell structure formed to engage with and immovably hold the strips or sections of wood in position, all danger of the roller shrinking 30 will be overcome. And it will also be understood that by means of the screw or bolt connection between the supporting tube or shell and the fastening ribs, a detachable fastening means is provided which readily permits 35 of the substitution of a new rib for one that may have become broken or otherwise damaged. The tube or shell 20 together with the keys or ribs 19 secured thereto comprise a section holder for the strips or sections 40 11. It will be further observed that the keys or ribs 19 are detachable from the tube or shell 20, thereby permitting of ready replacement of the keys or ribs whenever the same become damaged without involving 45 a substitution of a new tube or shell, or rendering necessary any change in said tube when renewing a broken or damaged key or rib. From this it follows that a great saving both in material and time is accomplished, which is a decided improvement in 50 the art, as heretofore the keys or ribs have been made integral with the tube or shell, and hence necessitates an entire new section holder for the strips or sections 11, whenever 55 said keys or ribs are damaged.

In the foregoing description and in the accompanying drawings I have described and illustrated a form of my invention that is fully capable of performing the work desired, yet I wish it to be understood that I do not limit myself to the precise details 60 therein shown and described, reserving for myself any and all modifications thereof as fall within the spirit and scope of the appended claims.

I claim as my invention:—

1. A roller comprising a plurality of longitudinally arranged strips provided with cut away portions on the undersurface of their meeting edges, and an inner supporting frame consisting of a tube or shell provided with end rings or collars and a plurality of longitudinally arranged wedge-shaped locking members adapted to enter said cut-away portions of said strips. 70

2. A roller comprising a plurality of longitudinally arranged strips provided with cut away portions on the undersurface of their meeting edges which form longitudinal recesses, and an inner supporting frame 80 consisting of a shell or tube provided with end rings and a plurality of longitudinally arranged keys connected to said shell or tube and having a wedge shaped portion adapted to enter said recesses to hold the 85 strips in position.

3. A roller comprising a plurality of longitudinally arranged strips provided with cut away portions on the undersurfaces of their meeting edges which form longitudinal recesses, and an inner supporting frame 90 consisting of a tube or shell provided with end rings and a plurality of longitudinally arranged locking keys connected to said tube or shell and having a portion adapted 95 to enter said recesses to retain said strips in position.

4. A roller comprising a plurality of sections the undersurfaces of which are provided with recesses, a supporting frame having a portion adapted to enter said recesses, and end rings carried by said frame and provided with slots whereby they may be connected with a source of power. 100

5. A roller comprising an outer sectional shell, an inner supporting frame provided with end rings or collars, and means for detachably connecting the said end rings or collars of the supporting frame with a source of power. 105

6. A roller comprising a plurality of strips longitudinally arranged and provided with recesses in their undersurfaces, an inner supporting frame consisting of a tube or shell provided with end rings or collars and a plurality of longitudinally arranged locking keys adapted to engage with said recesses to retain said strips in position, and means for connecting the said end rings of the said inner supporting frame with a 115 source of power. 120

7. A roller comprising a plurality of strips longitudinally arranged and provided with recesses in their undersurfaces, an inner supporting frame consisting of a tube or shell carrying end rings provided with wedge-shaped slots, and a plurality of longitudinally arranged locking keys carried by said tube or shell adapted to enter said recesses to retain said strips in position. 125

8. A roller comprising a plurality of sections the under-surfaces of which are provided with recesses forming one member of a dovetail, an inner tube or shell, a plurality of strips connected to said tube or shell forming the other member of a dovetail and adapted to be forced within the recesses of the said sections, and end rings or collars carried by said tube or shell and provided 10 each with a wedge slot for detachably connecting said tube or shell with a source of power.
9. A roller comprising a plurality of sections the undersurfaces of which are pro-

vided with recesses at their meeting edges, a 15 tube or shell, a plurality of strips detachably connected with said tube or shell and adapted to be forced within said recesses of said sections, and end rings or collars for detachably connecting said tube or shell with a source 20 of power.

In testimony whereof I affix my signature in presence of two witnesses.

HENRY BRUBAKER.
